POTHEAD OR TERMINAL FOR ELECTRIC CABLES

Filed Dec. 10, 1932

UNITED STATES PATENT OFFICE

1,941,614

POTHEAD OR TERMINAL FOR ELECTRIC CABLES

Fred C. Meyer, Paterson, and George E. Moffitt,
East Paterson, N. J., assignors to The Okonite-
Callender Cable Company, Incorporated, Pat-
erson, N. J., a corporation of New Jersey

Application December 10, 1932
Serial No. 646,594

2 Claims. (Cl. 173—353)

This invention is directed to potheads or terminals for cables of the pressure type and in the drawing an embodiment of the invention has been shown in sectional elevation.

5 Referring to the drawing in detail, 1 designates the pipe enclosing the insulated conductor of the cable to be terminated, the insulation of the cable which may be impregnated paper, for instance, being provided with a sheath 2 of metal 0 tape terminating at 3 for example, 4 designating the paper insulation of the cable.

Screwed to the exterior of the cable pipe 1 is a flange 5 and bolted to this flange is a ring 6 which is screwed to the exterior of the lower end 5 of a sleeve 7 surrounding the insulated conductor and constituting a continuation of the cable pipe 1.

Intermediate its ends the sleeve 7 is threaded to receive a flange 8 to which is bolted a metal 0 cone 9 constituting the bottom of the terminal this cone 9 supporting the porcelain insulator 10 of the terminal which is sealed and bolted at its lower end as shown at 11 to the upper end of the cone.

5 The upper end of the sleeve 7 is threaded internally to receive and support a pressure tube 12 which in effect constitutes a continuation of the sleeve 7 and receives the insulated conductor of the cable. The pressure tube 12 is slightly 0 larger in internal diameter than the outside diameter of the insulated conductor of the cable so as to provide a space between the pressure tube and the insulation of the cable for oil or other insulating fluid under pressure with which 5 the pipe 1 of the cable is filled. The upper end of the pressure tube 12 is sealed, being provided with a ring 13 screwed upon the upper end of the tube and a cap plate 14 bolted to this ring.

To the upper end of the conductor 15 of the 0 cable is secured a connector 16 provided with a stem 17 which passes upwardly through the cap plate 14 and is screw-threaded, nut 18 drawing the connector to the cap plate. The upper end of the porcelain 10 is sealed by a plate 19 and the stem 1 of the connector 16 passes through this plate where it is provided with a nut 20.

About the pressure tube 12 is a built up tape structure of paper or varnished cambric designated 21 and about the lower end of this tape structure is shielding tape 22 contacting at its lower end with the upper end of the sleeve 7.

About the upper end of the varnished cambric or paper tape structure 21 and surrounding the pressure tube 12 are barrier tubes 23.

As above mentioned the pressure tube 12 is

maintained under internal pressure due to the pressure in the cable pipe 1, the exterior of the pressure tube, however, is under static pressure, the insulator 10, which is sealed at both ends being kept filled with fluid insulating material 60 such as oil, designated 24 under static pressure.

What we claim is:—

1. A terminal for electric cables of the pressure type, comprising in combination a ring or gland 65 screwed to the cable pipe, a sleeve for receiving the insulated cable conductor and constituting a continuation of the cable pipe, a ring screwed to the lower end of said sleeve and bolted liquid-tight to said first mentioned ring or gland, a ring carried by said sleeve intermediate its ends, a 70 cone bolted to said ring, a tubular insulator supported by said cone and sealed thereto at its lower end, means for sealing the upper end of said insulator, a pressure tube within said insulator for receiving the insulated cable conductor 75 screwed into the upper end of said sleeve and communicating therewith, a built up insulating structure about said pressure tube, and a metal shield about the lower end of said insulating structure and contacting with the upper end of 80 said sleeve.

2. A terminal for electric cables of the pressure type, comprising in combination a packing gland 85 secured to the end of the cable pipe, a vertically extending sleeve in line with said pipe, a ring secured to the lower end thereof and bolted to said gland to provide a liquid-tight joint between the cable pipe and said sleeve, a ring screwed upon said sleeve intermediate its ends, a metal cone bolted to said last mentioned ring, a hollow 90 insulator sealed to said cone, means for sealing the upper end of said insulator, a pressure tube for receiving the insulated cable conductor screwed into the upper end of said sleeve, means for sealing the upper end of the pressure tube, 95 a connector secured to the upper end of the cable conductor and passing through the upper end of the pressure tube to the upper end of the said insulator, means for securing the same to the upper end of the insulator, a built up insulating structure surrounding said pressure tube 100 intermediate its ends, metal shielding about the lower part of said insulation and contacting with said sleeve, barrier tubes about the upper end of said insulation, and fluid insulation under 105 static pressure filling said insulator, said fluid insulation being out of communication with the interior of the pressure tube.
